FOLDING TOILET SEAT

John V. Barnes, La Canada, Calif., assignor, by
mesne assignments, to Taylor-Phillips, Inc.,
Los Angeles, Calif., a corporation of California

Application October 18, 1946, Serial No. 703,925

3 Claims. (Cl. 4—239)

1

This invention relates to infants' toilet seats. Its general object is to provide a foldable, portable toilet seat that may be quickly attached to a full-sized toilet seat.

A specific object of the invention is to provide a toilet seat adapted to be folded into a compact package.

Another object is to provide a foldable toilet seat having means for attaching the seat to a full-sized toilet seat, said attaching means being foldable within the seat.

Another object is to provide a back rest for supporting an infant on the seat, which back rest is foldable or collapsible against the seat when the seat is folded, and is provided with simple means for supporting it in its extended position.

Another object of the invention is to provide a foldable toilet seat having a hinged pubic section adapted to be raised above the plane of the seat for use, and to be folded within the plane of the seat when the seat is not in use.

Another object of the invention is to provide a foldable seat which may be fairly simply constructed of cast metal or molded plastic material.

Other objects will become apparent in the ensuing specification, taken in connection with the appended drawings, in which:

Fig. 1 is a plan view of an infant's toilet seat embodying my invention, a portion thereof being broken away to better illustrate the construction;

Fig. 2 is a longitudinal, vertical, sectional view through the toilet seat shown attached to a full-sized toilet seat, taken as indicated by the line 2—2 of Fig. 1; and

Fig. 3 is a view, partially in section and partially in elevation, of the toilet seat in its folded condition.

As an example of one form in which the invention may be embodied, I have shown in the drawings a toilet seat embodying a front section 4 and a rear section 5 hinged together by double hinges each including a bar 6 and a pair of pins 7 and 8 passing through the respective ends of the bar 6 and through bosses 9 and 10 formed in the respective sections. Each of the seat sections 4 and 5 includes an arched wall 11 and a series of transverse strengthening webs 12, 13, and 14 respectively, the webs 14 constituting end walls which, when the seat is opened up, abut each other so as to rigidify the seat structure under the weight of a child seated thereon. The bars 6 are received in slots 15 in the bosses 9

and 10 and are adapted to bottom against thickened wall portions 16 which define the upper extremities of the slots 15 in the position of use. The engagement of the thickened wall portions 16 against the bars 6 assists in rigidifying the seat in its extended position.

Formed integrally with the web 12 of the rear section is a lug 17 in which is pivoted the trunnion portion 18 of an attachment hook 19. The hook 19 includes an end finger 20 which is adapted to yieldingly bear against the lower surface 21 of a full-size toilet seat, 22 with sufficient pressure to securely hold the infant's seat in position thereon, with the aid of the positioning pins 43 which are molded as an integral part of the webs 13. The grip of the hook 19 is improved by the employment of a rubber sleeve 23 which is slipped over the hook 19. The hook 19 is S-shaped, including a reversely hooked portion 24 which terminates in the trunnion 18. In its operative position shown in Fig. 2, it projects downwardly in a vertical plane. It is adapted to be folded upwardly to an inoperative position shown in Figs. 1 and 3, and in such position is disposed in a horizontal plane and received within the seat section 5, as indicated in Fig. 3.

I provide an arcuate back rest 25, each arm of which has at its end a finger 26 that extends at an obtuse angle to the body of the back rest. Each finger 26 has an elongated slot 27 through which extends a pin 28 mounted in the boss 9. In the elevated position of the back rest shown in Fig. 2, each finger 26 has its end portion received in a socket 29 in the boss 9. The pin 28 is so disposed that, in this position of the back rest, the finger 26 has its end portion projecting substantially below the pin 28, and thus the fingers 26 are braced between the pins 28 and the sides of the sockets 29 so as to rigidly support the back rest in its raised position.

The upper portions of the socket 29 are flared upwardly and rearwardly on their rear sides to provide spaces 30 which permit the fingers 26 to be tilted rearwardly, allowing the backrest to be folded against the upper surface of the seat section 5 as shown in Fig. 3. The lower ends of the fingers 26 are curved as at 31 concentric to the lower ends of the slots 27, so as to allow the back rest to be pivoted around the pins 28 when the fingers 26 have been drawn upwardly to bring the lower extremities of the slots 27 against the pins 28.

A belt 41 (comprising two belt sections each attached at one end to the back rest and connectable together at their other ends by a buckle 42)

is adapted to be secured around the body of an infant to hold it against falling.

It is to be noted that the hinge mechanism is completely covered by the toilet seat sections in their extended positions, the wall portions 16 coming together at the hinge line to cooperatively form a substantially continuous upper seating surface.

The seat sections are of molded or cast material. A preferred material is a molded synthetic resin or "plastic" material of a type which can be given a highly polished surface in the molding operation and which also lends itself to being colored in various colors. The sections are made in the form of hollow shells in order to avoid undue weight, and are braced by the transverse web members 12, 13, 14 in order to have adequate strength. The use of the hollow shell construction also provides for accommodating the attaching hook 19 in its folded position.

A public section 32 is hinged at 33 to the inner margin of the forward seat section 4, for movement between an operative position, shown in Fig. 2, in which it extends upwardly above the seat, to a folded position, shown in Fig. 3, in which it lies within the confines of the seat, i. e., between the planes of the upper and lower extremities thereof.

I claim:

1. In an infant's toilet seat, an annular seat member comprising an upwardly arched, downwardly opening shell providing a convex upper seating surface, and an attachment hook hinged beneath such shell substantially on the major axis thereof for swinging movement from a position projecting downwardly in a substantially vertical, longitudinal plane, in which position it is adapted to engage beneath the rear portion of a full-sized toilet seat, to a folded position lying in substantially a horizontal plane entirely within the confines of said shell.

2. In a folding infant's toilet seat, a pair of seat sections hinged together on a transverse axis for folding movement from extended positions in which they cooperate to define an annular seat to folded positions in which their under surfaces are brought together, an arcuate back rest having end portions hinged to the rear section for folding movement from a raised position in which it may function as a back support to a folded position lying closely adjacent the upper surface of the rear section, a public section hinged to the inner periphery of the forward section for movement from an operative position in which it projects upwardly above the plane of the seat to a folded position in which it is accommo-

dated within the confines of said forward section, and an attaching member comprising a hook pivoted to the under side of the rear section on substantially the major axis of the seat for folding movement from a position lying in a vertical plane and projecting downwardly to engage beneath the underside of the rear portion of the full-sized toilet seat to a folded position lying in a horizontal plane within the confines of the rear seat section, said rear seat section having a downwardly opening cavity to receive said attaching member.

3. In a folding infant's toilet seat, a pair of seat sections hinged together for movement to folded positions in which their under surfaces are brought together, an arcuate back rest having end portions disposed at an obtuse angle relative to the general plane thereof, the rear seat section having, adjacent its hinged connection to the other section, a pair of sockets having rectangular lower portions and flared upper portions, said lower portions being disposed at right angles to the general plane of the rear seat section, said back rest end portions having elongated slots, and hinge pins mounted in said rear seat section, traversing said sockets and extending through said slots, whereby said back rest may be shifted from a position in which it lies flatly against the upper face of said rear seat section with said end portions thereof accommodated in said flared socket portions, to a raised position in which said end portions are aligned with said rectangular socket portions and may thereupon be shifted longitudinally into said longitudinal socket portions and become locked therein so as to support said back rest in said raised position.

JOHN V. BARNES.
